M. Mattson.

Nasal Irrigator

N°75285

Patented Mar. 10, 1868

*D. L. & F. B. Sears, Witniss.
D. L. & F. B. Sears* Morris Mattson

United States Patent Office.

MORRIS MATTSON, OF NEW YORK, N. Y.

Letters Patent No. 75,285, dated March 10, 1868.

NASAL IRRIGATOR.

The Schedule referred to in these Letters Patent and making part of the same.

TO ALL WHOM IT MAY CONCERN:

Be it known that I, MORRIS MATTSON, of the city of New York, in the county of New York, and State of New York, have invented a new and useful Improvement in Instruments for Injecting the Nostrils, and which I call a Nasal Irrigator; and I do hereby declare that the following is a full, clear, and exact description thereof, and of its mode or manner of operation, reference being had to the accompanying drawings and to the letters of reference marked thereon, and making a part of this specification.

It has been for a long time known that a stream of water may be made to pass into one nostril and out of the other, thereby rendering it possible to wash and clean the cavities of the nose; and it has also been observed that such washing extended in some cases to the small cavity known as the frontal sinus, located between the eyebrows, and which becomes seriously affected in long-continued cases of catarrh, giving rise to distressing headaches, &c.

This discovery has enabled medical men to remove foul matters from the nasal cavities, by applying saline and other solutions of a deodorizing and healing nature.

The instrument heretofore generally used for such purpose has been that invented by Dr. Thudicum, of London, which consists of a glass vessel, generally holding about a couple of pints, to the bottom of which is attached a small rubber tube, two or three feet in length, with a stop-cock at its terminal extremity, to which is fixed a perforated nozzle of gutta percha or prepared rubber. The glass vessel being filled with the required fluid, is placed some distance above the head of the individual to be operated on, and the nozzle is then inserted in the nostril, when the fluid by its own pressure forces itself into one nostril and out of the other. Great care is required to insure an adequate fitting of the nozzle to the nostril, since if any fluid is allowed to escape from the nostril, the operation is difficult and troublesome. In making use of this instrument, several sizes of nozzles are requisite, in order that the instrument may be adapted to nostrils of different sizes. In this country the stop-cock is generally dispensed with, on account of the expense, and the tube is compressed by the thumb and fingers, to prevent the flow of the fluid until required. Sometimes the tube is converted into a siphon, and the flow of the fluid thus regulated.

Instead of the nozzle described, there is sometimes inserted into the terminal extremity of the rubber tube a perforated tube of glass, having a disk or collar of rubber about it, designed to press upon the external portion of the nostril, but generally a nozzle is used instead of such flattened disk. Such nozzle is usually made of soft rubber, and of a somewhat conical or cup-like form, to admit of easy insertion into the nostril. Flattened plugs of wood, soft rubber, and other substances are also sometimes used.

Such instrument is objectionable, as there must be kept on hand a number of nozzles or nasal plugs of different sizes, so as to accurately and properly close different nostrils, and thereby incurring considerable expense; and in making trials of different nozzles to obtain a properly-fitting one, two or three, or more, frequently have to be tried, none of which can properly be used again until they have been thoroughly cleansed. The process thus involves trouble, expense, and vexation.

The force of the stream of fluid descending from a glass vessel, as described, whether by the law of pressure, or by means of a siphon, is also not easily varied or controlled as required in different cases. Sometimes a very weak, gentle current can only be used, and in other cases a forcible current is necessary to dislodge and force out incrusted matter, scales, &c. Such instrument cannot therefore be adapted to the emergencies arising in medical practice.

The object of my invention is the production of an instrument which shall do away with the objections above mentioned, and at the same time be efficient, portable, economical, and easily kept clean. This I accomplish by making use of but a single nasal plug, instead of having a number of plugs or nozzles of different kinds, and I am able to dispense with the use of the elevated vessel to hold the fluid.

Figure 1 shows the entire apparatus or instrument.

Figure 2 is a vertical section of the plug.

In endeavoring to do away with the necessity for plugs of variable sizes, I found, after many experiments, that a single plug, when made in a proper form, would accurately close any nostril, large or small, and could

be satisfactorily used under different circumstances and cases. I thus do away with the necessity for a number of plugs.

The plug as devised by me, is shown at A, and is in form very nearly like the sharp half of an egg, or the half of an ellipse, with a circular base, α , and has a small aperture, 1, at the point, for the escape of the fluid. Such plug is generally from an inch to an inch and an eighth long, and has a base about three-fourths of an inch, but with such a base, the length of the plug may be somewhat shortened, and yet accomplish the purposes desired. These particular proportions are not absolutely essential, but indicate a plug which I have found, from actual practice, satisfactory and operative.

The gradual enlargement of the plug from its point towards its base, causes it to be readily adaptable to nostrils of different sizes, and such plug is found to close any nostril with all the accuracy and perfection required, without being projected into the nostril unduly, so as to prove inconvenient or uncomfortable.

The plug may be made of hard rubber, metal, wood, or any material having sufficient firmness, and is made hollow, so as to be rendered as light and convenient as possible, and to facilitate cleansing. No greater thickness is required than such as is sufficient to give its sides required stiffness. The opposite sides of such plug may be reduced a little, or the plug somewhat flattened, without essentially impairing its efficiency. Such plug screws at its base on to its seat, or to the rod b, so as to be readily detachable therefrom. Such construction renders it convenient to clean the plug both inside and out, whereas soft rubber plugs or nozzles are difficult to be kept clean.

Such hard tapering plug may be used in connection with a rubber tube, and an elevated vessel of water or fluid, as before described, but I have found it most convenient and efficient when connected with an elastic syringe, B, either with or without valvular arrangement; the latter is always preferred, as thereby the operator is enabled to inject much or little fluid, as he may desire. The elastic bulb B may be compressed slightly or forcibly, as the nature of the case may require, and thus there is no difficulty in obtaining either a gentle current, or one sufficient for the expulsion of hardened or encrusted matter from the nostril. Such syringe is provided, like ordinary syringes, with a suitable inlet-tube, C, and discharge-tube D, which may be of any length desired.

If desired for any reason, or by any practitioner, to use a siphon in connection with such nasal plug, a siphon can be quickly made by inserting the inlet-tube C in any vessel of water, and placing such vessel a little above the head of the patient, and the siphon action can be obtained by a compression of the elastic bulb B.

What I claim as my invention, and desire to secure by Letters Patent, is—

1. The nasal plug A, so shaped as to fit and close nostrils of different sizes, constructed substantially as described.
2. The combination of the nasal plug A, constructed substantially as described, with the syringe B C D, substantially as and for the purposes set forth.

MORRIS MATTSON.
